LIGHTING UNIT

Karl Mayer, 1975 Falardeau St., Montreal, Quebec, Canada, and Laszlo Velekei, 275 Pelletier, Ville de Jacques Cartier, Quebec, Canada

Continuation-in-part of design application Ser. No. 2,170, May 5, 1966. This application Sept. 11, 1967, Ser. No. 8,559

Term of patent 7 years

(Cl. D48—23)

FIG. 3

FIG. 5

FIG. 1

FIG. 4

FIG. 2

FIG. 6

FIGURE 1 is a side elevation view of the lighting unit of our new design;

FIGURE 2 is a top plan view of the lighting unit shown in FIGURE 1;

FIGURE 3 is a bottom plan view showing the lighting unit of FIGURE 1;

FIGURE 4 is a side elevation view showing another embodiment of the lighting unit of our new design;

FIGURE 5 is a top plan view of the lighting unit shown in FIGURE 4; and

FIGURE 6 is a bottom plan view of the lighting unit shown in FIGURE 4.

The dominant features of our new design reside in the portions shown in full lines.

This application is a continuation-in-part of application Ser. No. D. 2,170, filed May 5, 1966, and now abandoned.

We claim:

The ornamental design for a lighting unit, as shown and described.
